UNITED STATES PATENT OFFICE.

THOMAS J. BUTLER, OF HARRISON, NEW JERSEY.

SPEED-ACCELERATING MECHANISM.

Application filed August 14, 1925. Serial No. 50,285.

This invention relates, generally, to improvements in mechanical movements; and the invention has reference, more particularly, to a novel speed-accelerating device or mechanism, which lends itself more especially on board ship to the starting and speeding up of hydroplanes or air-planes, the plane moving slowly from its taxiing position with immediate accelerated speed, over a short space to its raised position and its flying departure from the ship, or the like.

While in the present specification of the invention, I have described the speed-accelerating device or mechanism as a starting means for hydroplanes and airplanes, I am fully aware that the herein-described speed-accelerating device or mechanism may be put to many other uses, where it is desired to obtain increased or accelerated speed.

The present invention, therefore, has for its principal object to provide a novel and simply constructed, as well as an efficiently operating speed-accelerating device or mechanism, which may be put to many uses, and which is especially adapted for use in the starting and increasing or accelerating of the speed of hydroplanes, airplanes, and the like.

Other objects of the present invention not at this time more particularly enumerated will be fully understood from the following detailed description of the invention.

With the various objects of the present invention in view, the invention consists, primarily, in the novel speed-accelerating device or mechanism hereinafter set forth; and, the invention consists, furthermore, in the novel arrangements and combination of the various devices and parts, as well as in the details of the construction of the said parts, all of which will be more fully described in the following specification, and then finally embodied in the clauses of the claims which are appended to and which form an essential part of the same.

The invention is illustrated in the accompanying drawings, in which:—

Figure 1 is a plan or top view of the accelerating device or mechanism illustrating its use as a starting and speeding-up means for hydro-planes; Figure 2 is a side elevation of the device, with a portion of the main carrier being represented in section; and Figure 3 is a part plan view and part horizontal section of the accelerating device or

mechanism, with the hydroplane omitted from said view.

Figure 4 is a plan view of the forward portion of the device, on an enlarged scale, showing the releasing position of a certain part of the device, at the time that the hydroplane is about to rise with accelerated speed from the runway of the device.

Figure 5 is an end-view of the plane-carrier, looking in the direction of the arrow *x* in said Figure 3; Figure 6 is a transverse vertical section taken on line 6—6 in said Figure 3, also looking in the direction of the arrow *x*; and Figure 7 is a similar section taken on line 7—7 in said Figure 4, looking in the direction of the arrow *y*.

Similar characters of reference are employed in all of the said above described views, to indicate corresponding parts.

Referring now to the said figures of the drawings, the reference-character 1 indicates a main support or carrier, usually of a chambered or hollow structure, which is suitably secured in a fixed position upon the deck of a ship, but which may be secured in any other desired location, as will be evident.

As indicated more particularly, in Figure 2 of the drawings, the said main support or carrier 1 has suitably secured thereon, by means of bolts 2, or otherwise, in a suitable location, a suitably constructed base-plate 3 with which is associated a suitably constructed turn-table, as 4, which may be rotated by means of an actuating gear-mechanism 5, for bringing the runway 6 of the device horizontally into desired angular positions, as indicated in Figure 1 of the drawings. The said runway is made in the form of a long box-like element comprising an upper face-plate 7, bounded by downward projecting and longitudinally extending side-walls 8 and 9, to which is suitably secured a base-plate 10, carrying upon its outer and lower face the above-mentioned turn-table member 4. The respective end-portions of the said box-like element may be preferably closed, as will be understood. Extending laterally across the end-portion 11 of the face-plate 7 is a stop-block, as 12, and at its other end-portion 13, the said plate 7 has secured thereto by means of bolts 14, or otherwise, a casting or block 15, formed with a centrally disposed and longitudinally extending releasing element, as 16, having a projecting portion 17 which is pointed or V-shaped, sub-

100
105
110

stantially as shown in Figures 1, 3 and 4 of the drawings. On opposite sides of the said element 16, the casting or block 15 is also provided with longitudinally extending and upwardly projecting tubular members, as 18 and 19, substantially as shown, and the purposes of which will be hereinafter more fully set forth. As shown, the said face-plate 7 is also made with a centrally disposed and longitudinally extending opening or slot 20 which extends from the said stop-block 12 to a point 21, as indicated in Figure 3 of the drawings, and above which latter portion of the said opening or slot the said pointed or 15 V-shaped portion 17 of the releasing member 16 extends.

As indicated, the speed-accelerating means, which is suitably disposed within the chamber provided by the box-like runway 6 comprises a series of spindles arranged in pairs, in this case eight pairs of such spindles being employed, and which are respectively indicated by the reference-characters 22 and 23, 24 and 25, 26 and 27, 28 and 29, 30 and 31, 25 32 and 33, 34 and 35, and 36 and 37, the respective spindles having their respective end-portions rotatably journaled in suitably disposed holes or bearings with which the face-plate 7 and the base-plate 10 are provided. 30 One of the said spindles, as 31, however, is of greater length than the other spindles, and it extends in a downward direction through the top of the main support or carrier 1, said downwardly extending portion of said spindle 31 being adapted to be actuated from a suitable source of power by gearing, or otherwise. Rotation from the spindle 31 is transmitted to the spindle 30 by means of a gear-wheel 39 suitably mounted upon the spindle 31 which is in mesh with a gear-wheel 38 correspondingly mounted upon the spindle 30. Mounted upon the upper portion of the spindle 22 is a large sprocket wheel or pulley 40 and upon the 45 upper portion of the spindle 24 is a small sprocket-wheel or pulley 41, while similarly disposed upon the upper portion of the spindle 23 is a large sprocket-wheel or pulley 42, and upon the upper portion of the spindle 25 is a small sprocket-wheel or pulley 43.

Upon the lower portion of the spindle 24 is a large sprocket-wheel or pulley 44 and upon the lower portion of the spindle 26 is a small sprocket-wheel 45. Similarly mounted upon the spindle 25, upon the lower portion thereof, is a large sprocket-wheel or pulley 46 and upon the lower portion of the spindle 27 is a small sprocket-wheel or pulley 47. Upon the upper portion of the spindle 26 is a large sprocket-wheel or pulley 48 and upon the upper portion of the spindle 28 is a small sprocket-wheel or pulley 49. Similarly mounted upon the upper portion of the spindle 27 is a large sprocket-wheel or pulley 50 and upon the upper por-

tion of the spindle 29 is a small sprocket-wheel or pulley 51. Mounted upon the lower portion of the spindle 28 is a large sprocket-wheel or pulley 52 and mounted upon the lower portion of the spindle 30 is 70 a small sprocket-wheel or pulley 53. Mounted upon the lower portion of the spindle 29 is a large sprocket-wheel or pulley 54, and mounted upon the lower portion of the spindle 31 is a small sprocket-wheel or pulley 75 55. Mounted upon the upper portion of the spindle 30 is a large sprocket-wheel or pulley 56, and mounted upon the upper portion of the spindle 32 is a small sprocket-wheel or pulley 57. Mounted upon the 80 upper portion of the spindle 31 is a large sprocket-wheel or pulley 58, and mounted upon the upper portion of the spindle 33 is a small sprocket-wheel or pulley 59. Mounted upon the lower portion of the spindle 32 85 is a large sprocket-wheel or pulley 60, and mounted upon the lower portion of the spindle 34 is a small sprocket-wheel or pulley 61. Mounted upon the lower portion of the spindle 33 is a large sprocket-wheel or pulley 62, and mounted upon the lower portion of the spindle 35 is a small sprocket-wheel or pulley 63. Upon the upper portion of the spindle 34 is a large sprocket-wheel or pulley 64, and mounted upon the upper portion of the spindle 36 is a small sprocket-wheel or pulley 65.

Similarly mounted upon the upper portion of the spindle 35 is a large sprocket-wheel or pulley 66, and mounted upon the upper portion of the spindle 37 is a small sprocket-wheel or pulley 67.

Link-chains or belts 68 are passed over the respective large and small sprocket-wheels or pulleys of the respective spindles, as indicated in said Figure 3 of the drawings, and upon the respective spindles, intermediate the sprocket-wheels or pulleys upon the spindles, are suitable propelling discs or wheels 69 and 70, 71 and 72, 73 and 105 74, 75 and 76, 77 and 78, 79 and 80, 81 and 82, and 83 and 84, mounted upon the respective spindles 22, 23, 24, 25, 26, 27, 28, 29, 30, 31, 32, 33, 34, 35, 36 and 37.

From an inspection of said Figure 3 of the drawings, it will readily be seen, that owing to the arrangement of the respective sprocket-wheels or pulleys, as well as of the respective propelling discs or wheels, the speed of these various members located to the left of the spindles 30 and 31 will increase, while the speed of the various members to the right of the said spindles will decrease, so that an accelerated speed from right to left of the device or mechanism will be the result.

Movably mounted upon the herein-above described runway 6 is a plane-carrier or carriage, as 85, which consists, essentially, of a suitably shaped plate 86, formed at its 130

side-edges with downwardly extending members or legs 87 formed with inwardly projecting hubs 88 provided with pintles 89 carrying wheels or rollers 90. These wheels or rollers 90 may also be provided upon their peripheries with annular guide-flanges 91 which fit and roll within correspondingly located grooves or channels 92 in the base-plate 10 to prevent lateral displacement of the carrier or carriage 85 when in its embracing relation with the runway 6, as indicated in Figure 6 of the drawings. Anti-friction rollers 93, or other suitable means, may be placed between the members or legs 87, which rollers extend laterally across and are adapted to move upon the face-plate 7 of the runway, so that the carrier or carriage 85 may have a free movement thereon. Extending downwardly from the plate 86 into and through the longitudinally extending opening or slot 20 in the face-plate 7 is a stud 94 which carries a disc or wheel-engaging member 95 of such width and length that it will be properly engaged by the pairs 23 of propelling discs, so as to move the carriage or carrier 85 in a forward or backward direction upon the runway 6, according to the direction of rotation of the spindle 31. The said plate 86 is also provided upon its upper face with longitudinally extending tubular elements or cylinders 96 in which are movably disposed portions 98 of bumper-rods 97. Each bumper-rod 97 is also provided with an enlargement, as 99, and extending forwardly from said enlargements 99 are rod-portions 100 which are adapted to enter and be received by the tubular members 18 and 19, substantially as indicated in Figure 4 of the drawings. Buffer or shock-absorbing springs 101 encircle the bumper-rods 97, between the enlargements 99 and the end-portions 102 of the tubular elements or cylinders 96, as shown. The plate 86 of the carriage or carrier is also provided with a centrally disposed and upwardly projecting post, as 103, upon which are pivotally mounted the arms 104 and 105 of suitably constructed tongs. As shown, the arm 104 comprises a pair of members 106 and 107, and the arm 105 a pair of members 108 and 109, the members 107 and 109 being connected by a spring 110, substantially as shown. At their rear end-portions, the said members 107 and 109 are formed with extensions 111 and 112, said extensions being respectively provided with upwardly projecting engaging members, preferably in the form of right-angled flanges 113 and 114 which are adapted to be brought into contact with the end-portions of the usual pontoons 116 of the hydro-plane or aeroplane in the manner and for the purposes to be presently described.

The pontoons 116, as usual, are connected by laterally extending members, as 117,

which form part of the usual frame 118 of the hydroplane.

The operation for starting the flying machine, and for accelerating the initial movements, to cause the flying machine to rise 70 under a minimum amount of space, briefly, is as follows:—

Suppose the carrier or carriage 85 having been moved to the extreme right-hand end-portion 11 of the runway 6, with the flanges 113 and 114 of the tongs resting against the stop-block 12, the speeding-up or accelerating mechanism also being at rest.

By the usual means, the hydroplane is lifted and placed above the carrier or carriage 85, with the cross-member or members 117 of the frame 118 of the plane resting directly upon the longitudinally extending tubular elements or cylinders 96 of the said carrier or carriage 85.

The speeding or accelerating mechanism is now set in motion, by operating the main shaft or spindle 31 in the proper direction. The rotary gripping action of the propelling wheels or discs 69 and 70 in frictionally gripping the member 95 of the carrier or carriage start the latter in the direction of the arrow α , as indicated in Figure 2 of the drawings, with the result that the faster rotating discs or wheels 71 and 72, 73 and 74, 75 and 76, 77 and 78, 79 and 80, 81 and 82, and 83 and 84, will in succession grip the member 95, thus causing the carrier or carriage to move upon the runway 6 from a normally slow speed to a constantly increasing or accelerated maximum speed. At the same time, the flanges or ribs 113 and 114 being in contact with the end-portions of the portions 116 of the hydro-plane, the latter will also be carried in a forward direction with the carrier or carriage 85, as will be evident.

While thus being moved in its forward direction, the operator of the flying machine also starts the motor of the machine.

As soon as the carrier or carriage, with the maximum increased speed, reaches the forward portion of the runway 6, the pointed or V-shaped portion 17 of the releasing member 16 enters between the members 106 and 108 of the respective arms 104 and 105, causing said members to separate in the directions of the arrows $u-u$, as indicated in Figure 4 of the drawings, and consequently withdrawing the ribs or flanges 113 and 114 of the members 107 and 109 from their active engagement with the end-portions of the pontoons 116 of the flying machine. At this time, also, the carrier or carriage 85 having come in contact with the bumper-springs 101, its forward movement is arrested, but the flying machine, owing to the accelerated speed received from the mechanism, during this taxiing or jockeying movement, and under its own speed, is lifted

from the carrier or carriage to fly away into space, under the guidance of its operator. Simultaneously with the stopping of the carrier or carriage 85, the rotation of the main shaft or spindle 31 is reversed, thus causing the accelerating mechanism to return the carrier or carriage to its starting position at the end-portion 11 of the runway 6.

10 While in the above I have described the use of my invention in connection with the starting of hydro-planes from the decks of battleships and other vessels, it will also be evident that the principles of the accelerating mechanism may also be used for lifting aeroplanes into the air, and that the mechanism may also be used for other purposes where increased or accelerated speed is desired.

15 20 I am also fully aware, that changes may be made in the general arrangements and combinations of the various devices and parts, as well as in the details of the construction of the said parts, without departing from the scope of the present invention, as set forth in the foregoing specification, and as defined in the clauses of the claims which are appended thereto. Hence, I do not limit my present invention to the exact arrangements and combinations of the various devices and parts as described in the said specification, nor do I confine myself to the exact details of the construction of the said parts, as illustrated in the accompanying drawings.

25 I claim:—

30 1. A speed-accelerating means comprising a series of pairs of opposed rotatable propelling discs, and means for progressively accelerating the rotary speed of successive pairs of said discs.

35 40 45 50 2. A speed-accelerating means comprising a longitudinal series of pairs of transversely opposed rotatable spindles, a propelling disc mounted upon each spindle, and means cooperating with said spindles for progressively accelerating the rotary speed of successive pairs of spindles and the propelling discs carried thereby.

55 60 65 3. A speed-accelerating means comprising a series of rotatably disposed spindles, said spindles being arranged in pairs, and one of said spindles serving as a main driving spindle, a propelling disc mounted upon each spindle, a gear upon said main driving spindle, and a gear upon the corresponding spindle in mesh with the gear of the main driving spindle, and means associated with the complement of spindles for variously rotating the speed of the spindles and propelling discs.

relation with said carriage for moving the carriage upon said runway, and means associated with said spindles for accelerating the rotary speed of the spindles and propelling discs, and for moving the carriage with accelerating speed from one end of the runway to the other end thereof.

10. In an apparatus of the character specified, a runway, a carriage movably disposed upon said runway, said carriage being adapted to receive thereon a flying machine, a series of spindles rotatably disposed upon said runway, said spindles being arranged in pairs, and one of said spindles serving as a main driving spindle, propelling discs mounted upon said spindles in frictional relation with said carriage for moving the carriage upon said runway, a gear upon said main driving spindle, and a gear upon the corresponding spindle in mesh with the gear of the main driving spindle, and means associated with the complement of spindles for variously rotating the speed of the spindles and propelling discs.

25. 11. In an apparatus of the character specified, a runway, a carriage movably disposed upon said runway, said carriage being adapted to receive thereon a flying machine, a series of spindles rotatably disposed upon said runway, said spindles being arranged in pairs, and one of said spindles serving as a main driving spindle, propelling discs mounted upon said spindles in frictional relation with said carriage for moving the carriage upon said runway, a gear upon said main driving spindle, and a gear upon the corresponding spindle in mesh with the gear of the main driving spindle, and means associated with the complement of spindles for decreasing the speed of the spindles and propelling discs located on one side of the main driving spindle, and for increasing the speed of the spindles and propelling discs located on the opposite side of the main driving spindle.

45. 12. In an apparatus of the character specified, a runway, a carriage movably disposed upon said runway, said carriage being adapted to receive thereon a flying machine, a series of spindles rotatably disposed upon said runway, said spindles being arranged in pairs, and one of said spindles serving as a main driving spindle, propelling discs mounted upon said spindles in frictional relation with said carriage for moving the carriage upon said runway, a gear upon said main driving spindle, and a gear upon the corresponding spindle in mesh with the gear of the main driving spindle, and means associated with the complement of spindles for decreasing, in succession, the speed of the spindles and propelling discs located on one side of the main driving spindle, and for

accelerating, in succession, the speed of the spindles and propelling discs located on the opposite side of the main driving spindle.

13. In an apparatus of the character specified, a runway, a carriage movably disposed upon said runway, said carriage being adapted to receive thereon a flying machine, means associated with the runway for moving the carriage thereon, mechanism carried by said carriage for maintaining the flying machine in position upon the carriage during the forward movement of the carriage, consisting of a pair of spring-controlled tong-members, each member being provided with an engaging flange adapted to be brought into engagement with portions of the flying machine, and means carried by said runway for actuating said tong-members, so as to release said engaging flanges from engagement with the flying machine.

14. In an apparatus of the character specified, a runway, a carriage movably disposed upon said runway, said carriage being adapted to receive thereon a flying machine, means associated with the runway for moving the carriage thereon, mechanism carried by said carriage for maintaining the flying machine in position upon the carriage during the forward movement of the carriage, consisting of a pair of spring-controlled tong-members, each member being provided with an engaging flange adapted to be brought into engagement with portions of the flying machine, means carried by said runway for actuating said tong-members, so as to release said engaging flanges from engagement with the flying machine, and means also carried by said runway for arresting the movement of the carriage after release of the flying machine from the carriage.

15. In an apparatus of the character specified, a runway, a carriage movably disposed upon said runway, said carriage being adapted to receive thereon a flying machine, means associated with the runway for moving the carriage thereon, mechanism carried by said carriage for maintaining the flying machine in position upon the carriage during the forward movement of the carriage, consisting of a pair of spring-controlled tong-members, each member being provided with an engaging flange adapted to be brought into engagement with portions of the flying machine, and a releasing element carried by said runway, said releasing element having a pointed end-portion adapted to enter between said tong-members, so as to release said engaging flanges from engagement with the flying machine.

In testimony, that I claim the invention set forth above I have hereunto set my hand this 31st day of July, 1925.

THOMAS J. BUTLER.
